Primary Examiner — L. Martinez(74) *Attorney, Agent, or Firm* — Richard A. Fagin(57) **CLAIM**

I claim the ornamental design for an extrusion, substantially as shown and described.

DESCRIPTION

FIG. 1 is a top, front perspective view of an extrusion showing my new design;

FIG. 2 is a bottom, rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The double broken lines in the various figures indicate that the design is of indefinite length and do not form part of the claimed design.

The extrusion is shown with a symbolic break in its length. The appearance of any portion of the extrusion between the jagged break lines forms no part of the claimed design.
